UNITED STATES PATENT OFFICE

WILLIAM GOWIE, OF CANTON, OHIO, ASSIGNOR TO THE HARVARD COMPANY, OF CANTON, OHIO, A CORPORATION OF OHIO

ELECTRICAL DISTRIBUTING AND CONTROL APPARATUS FOR DENTAL INSTRUMENTS AND THE LIKE

Application filed September 9, 1929. Serial No. 391,153.

The invention relates to electrical apparatus including a transformer receiving power from a standard 110 volt 60 cycle power line, and a switch panel including resistances, switch gear, and suitable connectors for a plurality of electrodental instruments, each of which may require a different voltage and a different current, and the switch panel being adapted for mounting 10 on a dental unit.

The maximum voltages and amperes required to operate the usual electrodental instruments may be as follows:

Cautery	3 volts, 10.0 amps.
Mouth and antrum lamps	12 volts, 0.16 amps.
Syringe	12 volts, 1.5 amps.
All other instruments, such as spatulas, root canal driers, pluggers, etc.	4 volts, 2.2 amps.

Due to the foregoing voltage and current differences, it has been customary to provide a separate transformer and a separate switch and cord for each instrument, and such equipment adds considerable to the total cost of the dental unit, and requires a 30 relatively large total space on or near the unit.

On the other hand some of the instruments may be used in ordinary practice but once or twice a month.

The total space required for separate transformers and switches for the several instruments has not however been very much greater than that which would be required for a centralized distributing and control 40 apparatus designed and constructed according to standard electrical engineering practice.

Moreover for a centralized apparatus designed to operate any of the foregoing electrodental instruments, the apparatus must 45 not only be compact and occupy a minimum space on the dental unit, and must not only efficiently deliver the proper currents under the definite control, but must also be so arranged that the inadvertent connection of

one instrument with the wrong output connectors of the distributing and control apparatus will not damage the apparatus.

Accordingly the objects of the present improvements include the provision, particularly for use on a dental unit, of electrical distributing and control apparatus for dental instruments and the like, which shall be very compact and occupy a relatively small space, which shall include a plurality of output connectors each adapted for delivering under variable control a different voltage and/or current, and which shall be so arranged as to preclude damage thereto by inadvertent connection of an instrument 60 with the wrong connectors.

These and other objects are attained in the present improvements, as will hereinafter be set forth in detail and claimed.

A preferred embodiment of the invention 70 is illustrated in the accompanying drawings forming part hereof, in which

Figure 1 is a fragmentary side elevation of the improved electrical distributing and control apparatus for dental instruments and the like, detached from its mounting on a dental unit;

Fig. 2, a fragmentary rear elevation thereof; and

Fig. 3, a fragmentary diagrammatic view 80 illustrating the electrical relationships of the several parts of the apparatus.

Similar numerals refer to similar parts throughout the several views.

The improved electrical distributing and control apparatus is indicated generally at 85 10 and includes a novel transformer 11, and a novel switch and resistance unit 12.

The transformer 11 includes a primary winding 13, the terminals of which are adapted for connection with a standard 110 volt 60 cycle power line.

The secondary 14 of the transformer includes a coil 14a of relatively high resistance wire connected in series with a coil 14b of relatively low resistance wire.

A conductor 15 connects the junction 16 between the ends of the secondary coils with one binding post 17 on the switch and resistance unit 12; a conductor 18 connects 100

the outer end of the high resistance coil 14a with another binding post 19 on the unit 12; and a conductor 20 connects the outer end of the low resistance coil 14b with a binding post 21 on the unit 12.

For convenience in assembly and maintenance, the conductor 15 is covered with yellow colored insulation; the conductor 18 is covered with red colored insulation; and the conductor 20 is covered with black colored insulation.

The switch and resistance unit 12 includes a panel 22 preferably of insulating material upon the rear and at the bottom of which a common bus bar 23 is mounted and connects with the binding post 21 to which the black wire 20 leads.

For convenience in making rapid connections with the several instruments to be served by the switch and resistance unit, three jacks 24a, 24b, and 24c are mounted at the bottom of the panel 22, and similar connector members 25a, 25b, and 25c, respectively, of the jacks are connected with the common bus bar 23.

At the upper end of the panel 22, variable resistances or rheostats 26a and 26c are mounted, and between the resistances 26a and 26c and the bus bar 23, a variable resistance or rheostat 26b is mounted.

The rheostats are preferably of the wire wound type, and include respectively resistance coils 27a, 27b, and 27c and rotatable contact arms 28a, 28b, and 28c, respectively.

The contact arms are mounted respectively on shafts 29a, 29b, and 29c, which extend from the location of the coils and arms on the back of the panel 22 through suitable bearing apertures in the panel to the front side thereof, and knobs 30a, 30b, and 30c (not shown) are secured respectively on the outer ends of the shafts.

The other connector member 31a of the jack 24a is connected by a conductor 32a with one terminal of the resistance coil 27a; and similarly the other connector member 31c of the jack 24c is connected by a conductor 32c with one terminal of the resistance coil 27c.

The other connector member 31b of the jack 24b is connected by a conductor 32b with the contact arm 28b.

A conductor 33 connects the contact arms 28a and 28c and the binding post 17.

One terminal of the resistance coil 27b is connected with a terminal of a fuse 34, the other terminal of which is connected with the binding post 19.

The coils 14a and 14b of the transformer are proportioned so that the potential between the black conductor 20 and the yellow conductor 15 is 4 volts, and the potential between the black conductor 20 and the red conductor 18 is 12 volts.

The coil 27a has a maximum resistance

of 0.25 ohms and the coil 27c has a maximum resistance of 3.0 ohms; while the coil 27b has a maximum resistance of 150 ohms.

Accordingly the potential between the connector members of the jack 24a, served by the black conductor 20 and the yellow conductor 15 through the low resistance rheostat 26a is 4 volts, thus permitting a flow of a relatively heavy current, and the jack 24a is adapted for selective connection with a plug 35 at one end of a conductor cable, the other end of which is connected with a socket. A cautery may be inserted in the socket and served from the jack 24a.

The yellow conductor 15 having a common connection not only with the rotary arm 28a of the low resistance rheostat 26a, but also with the rotary arm 28c of the high resistance rheostat 26c, also delivers 4 volt's under proper control to the jack 24c, and when the plug 35 is inserted in this jack, instruments such as a plugger requiring 4 volts and a relatively low amperage may be served.

If by mistake the plug 35 is inserted in the jack 24c when the cautery is connected with the plug, no damage will be done, because of the relatively high resistance of the rheostat 26c.

It is apparent that both rheostats 26a and 26c are served by the same conductors from the transformer, and that the jacks 24a and 24c served thereby deliver different currents at the same voltage, and that the operation of one rheostat has no effect on the other, the contact arms and coils being in parallel.

The potential between the connector members of the jack 24b is 12 volts for serving a mouth lamp connected with the plug 35, and the fuse 34 protects the transformer in the event that the cautery is plugged into the 12 volt jack 24b by mistake.

If the lamp is plugged in either of the 4 volt jacks, no damage will be done, and the lamp will only be partially illuminated.

I claim:

1. Electrical distributing and control apparatus for dental instruments and the like including a transformer and a switch unit, the switch unit including a plurality of sets of contact members, and a variable resistance for each set of contact members, and the transformer including a primary and a secondary, a conductor connecting one contact member of each set with the similar contact members of the other sets and with one terminal of the transformer secondary, the variable resistances including members movable with respect to each other, a conductor connecting similar members of a plurality of the variable resistances with each other and with another point on the transformer secondary coil, and conductors each connecting another member of each variable resistance with the other contact member of the sets, respectively.

2. Electrical distributing and control apparatus for dental instruments and the like including a transformer and a switch unit, the switch unit including a plurality of sets of contact members, and a variable resistance for each set of contact members, the transformer including a primary and a secondary, a conductor connecting one contact member of each set with the similar contact members of the other sets and with one terminal of the transformer secondary, the variable resistances including members movable with respect to each other, and a conductor connecting the other terminal of the transformer secondary with one of the members of one of the variable resistances, a conductor connecting similar members of some of the variable resistances with each other and with an intermediate point on the transformer secondary coil, and conductors each connecting another member of each variable resistance with the other contact member of the sets, respectively.

3. Electrical distributing and control apparatus for dental instruments and the like including a transformer and a switch unit, the switch unit including a plurality of jacks, and a variable resistance for each jack, and the transformer including a primary and a secondary, a conductor connecting one contact member of each jack with the similar contact members of the other jacks and with one terminal of the transformer secondary, the variable resistances including members movable with respect to each other, a conductor connecting similar members of a plurality of the variable resistances with each other and with another point on the transformer secondary coil, and conductors each connecting another member of each variable resistance with the other contact member of the jacks, respectively.

4. Electrical distributing and control apparatus for dental instruments and the like including a transformer and a switch unit, the switch unit including a plurality of jacks, and a variable resistance for each jack, the transformer including a primary and a secondary, a conductor connecting one contact member of each jack with the similar contact members of the other jacks and with one terminal of the transformer secondary, the variable resistances including members movable with respect to each other, and a conductor connecting the other terminal of the transformer secondary with one of the members of one of the variable resistances, a conductor connecting similar members of some of the variable resistances with each other and with an intermediate point on the transformer secondary coil, and conductors each connecting another member of each variable resistance with the other contact member of the jacks, respectively.

5. Electrical distributing and control apparatus for dental instruments and the like including a transformer and a switch unit, the switch unit including a plurality of sets of contact members, and a variable resistance for each set of contact members, the transformer including a primary and a secondary, the secondary including a relatively high resistance coil connected in series with a relatively low resistance coil, a conductor connecting one contact member of each set with the similar contact members of the other sets and with one terminal of the transformer secondary, the variable resistances including members movable with respect to each other, and a conductor connecting the other terminal of the transformer secondary with one of the members of one of the variable resistances, a conductor connecting similar members of some of the variable resistances with each other, and with the connection between the high resistance coil and low resistance coil of the transformer secondary, and conductors each connecting another member of each variable resistance with the other contact member of the sets, respectively.

6. Electrical distributing and control apparatus for dental instruments and the like including a transformer and a switch unit, the switch unit including a plurality of jacks, and a variable resistance for each jack, the transformer including a primary and a secondary, the secondary including a relatively high resistance coil connected in series with a relatively low resistance coil, a conductor connecting one contact member of each jack with the same contact members of the other jacks and with one terminal of the transformer secondary, the variable resistances including members movable with respect to each other and a conductor connecting the other terminal of the transformer secondary with one of the members of one of the variable resistances, a conductor connecting similar members of some of the variable resistances with each other and with the connection between the high resistance coil and the low resistance coil of the transformer secondary, and conductors each connecting another member of each variable resistance with the other contact member of the jacks, respectively.

In testimony that I claim the above, I have hereunto subscribed my name.

WILLIAM GOWIE.
